UNITED STATES PATENT OFFICE.

PHILETUS W. GATES, OF CHICAGO, ILLINOIS, ASSIGNOR TO THE GATES IRON WORKS, OF SAME PLACE.

DESIGN FOR A FRAME FOR ORE-CRUSHERS.

SPECIFICATION forming part of Design No. 34,032, dated February 5, 1901.

Application filed May 28, 1900. Serial No. 18,326. Term of patent 14 years.

To all whom it may concern:

Be it known that I, PHILETUS W. GATES, a citizen of the United States, residing at Chicago, in the county of Cook and State of Illinois, have invented and produced a new and original Design in Frames for Ore-Crushers, of which the following is a specification, reference being had to the accompanying drawings, forming a part hereof.

10 In the accompanying drawings, Figure 1 represents a perspective view of an ore-crusher frame, showing my design; and Fig. 2, a plan view, partly in section.

As shown in the drawings, the leading or 15 material feature of my design consists of an annular frame portion A, provided with a lower annular flange B, an upper annular por-

tion C, and a flange D, intermediate the lower portion and the upper portion, having lugs or projections E. The center of the frame, as 20 at G, is bored clear through from end to end.

Having described my invention, what I claim as new, and desire to secure by Letters Patent, is—

The design for a frame for an ore-crusher 25 as herein shown and described.

In testimony whereof I have signed my name to this specification in the presence of two subscribing witnesses.

PHILETUS W. GATES.

Witnesses:

H. M. VANCE,
EDW. V. SHERLOCK.
